UNITED STATES PATENT OFFICE.

ALFRED NORTON GOLDSMITH, OF NEW YORK, N. Y., ASSIGNEE, BY MESNE ASSIGNMENTS, TO RADIO CORPORATION OF AMERICA, A CORPORATION OF DELAWARE.

APPARATUS FOR WAVE CHANGING IN RADIOSIGNALING.

Application filed July 31, 1919. Serial No. 314,479.

To all whom it may concern:

Be it known that I, ALFRED N. GOLDSMITH, a citizen of the United States, and a resident of the borough of Manhattan, city, 5 county, and State of New York, have invented certain new and useful Improvements in Apparatus for Wave Changing in Radiosignaling, of which the following is a specification accompanied by drawings.

10 This invention relates to radio signaling, but more particularly to a method and apparatus for wave changing.

The primary object of the invention is to provide a ready means of changing the inductance of the desired circuits conveniently and continuously, especially applicable for fine tuning or coarse tuning of antennæ and secondary circuits, to produce simple transmitting and receiving wave changers in 20 which the variable elements may be controlled if desired by the manipulation of a single operating handle or other controlling device, thus forming a uni-control transmitter or receiver, without multiplication of 25 parts.

I have found that an inductance in the field of which a conducting shield forming a short circuited secondary is adapted to be moved in one direction or another, or periodically introduced and withdrawn, forms an efficient and satisfactory means for changing wave length. The variable inductance elements and the usual variable capacities may be so connected together mechanically 30 that one operating movement only is necessary for changing wave length. If desired, the usual bi-control or multi-control set may be provided in which two or more movements are necessary depending upon the operative 35 mechanical connections provided. Obviously, my invention contemplates relative movement between a coil or coils and a shield or shields however this may be accomplished.

40

Preferred forms of apparatus for practicing my method of wave changing are illustrated in the accompanying drawings in which:

Fig. 1 is a diagrammatic representation 45 partly in perspective of circuits and apparatus showing a receiving station provided with a variable shield inductance;

Fig. 2 is a similar view of a modified form of variable loading inductance;

Figs. 3 and 4 views of further modifications of shield inductances;

Fig. 5 is a diagrammatic view partly in section showing a modified form of inductance;

Fig. 6 is a diagrammatic view illustrating a constructional detail of one form of shield; 60

Fig. 7 is a diagrammatic view showing a modified form of shield inductance;

Fig. 8 is a detail side view of a modified form of shield;

Fig. 9 is a diagrammatic view partly in 65 section showing a modified form of inductance;

Fig. 10 is a diagrammatic view showing another form of shield inductance;

Fig. 11 is a diagrammatic view partly in 70 perspective showing a variable loading inductance and a variable coupling.

Referring to the drawings and at first more particularly to Fig. 1, A represents an antenna grounded at B and provided with 75 the coupling coil C coupled through coil D to suitable receiver circuits having the variable condenser F, detector G, and the telephones H. The usual variable condenser J is shown in the antenna A, and K represents 80 a simple form of shield inductance comprising a loading coil L and a shield O which may be in the form of a disk of conducting material as copper, and may be of any suitable configuration. 85

In Fig. 1 the shield O is so arranged relative to the coil L that the magnetic lines of force of the self-field of the inductance coil pass in part through said shield, and variations of current in the coil induce eddy currents in the shield as well understood, so that the shield constitutes a short circuited secondary to the coil, which may be regarded as its primary. The effect of the shield O is in general to reduce the inductance of coil 90 L as measured between its terminals. If the shield is moved or rotated in such a way relatively to or about any axis O', as to change the interlinkage of magnetic flux from the coil passing through the shield, its 100 reaction on the coil will be changed and the effective inductance of the coil will be altered.

Theory and practice agree in indicating 105 that the greatest reduction in the inductance of coil L occurs when the coupling between the coil and the eddy current paths set up in the shield O is unity. While unity coupling cannot be realized, sufficiently close couplings can be obtained to cause extremely 110

marked changes in the inductance of coil L. For example, in the modification shown in Fig. 3, which will be referred to in detail, the inductance of a coil may be reduced to 5 less than one twenty-fifth of its maximum value by the presence of two shields.

The shield inductance K, comprising the elements L and O, and the variable condenser J, form tunable circuit elements and 10 obviously they may be so mechanically connected that both may be controlled by manipulation of one operating handle or member, just as in Fig. 3 two shields O are shown mechanically connected to be moved 15 together. The shield inductance K and variable condenser J may also be connected if desired in the receiver circuits E in any suitable manner and thus form an ordinary tuned secondary. If the range of inductance variation in such a tuned circuit is 20 twenty to one, and range of capacity variation of the variable condenser in such circuit is also twenty to one, the circuit in question will have a range of frequency variation of twenty to one as well. By this means a tuning element covering a substantially long range of frequencies or wave lengths with a single control handle if desired may be obtained.

30 In Fig. 1 I have disclosed a method whereby the self-inductance of a coil can be altered continuously by the motion in the magnetic field of said coil of a shield or mass of conducting material.

35 In Fig. 2, I have shown the coils R and S connected in series in the antenna so that their fields assist each other. The self-field of coil R in part passes through the shield O, as also will a part of the self-field of 40 coil S. In addition, a portion of the mutual field of both coils will pass through the shield O. The introduction of the shield between the coils will therefore not only diminish the inductance of coils R and S, 45 but will in addition, diminish their mutual and assisting inductance, so that the inductance between the terminals of the coils will be markedly reduced. The motion of the shield as before described will give rise to 50 a continuous variation in the inductance. This construction shown in Fig. 2 is a combined shield inductance and variable shield mutual inductance.

55 It is possible to construct a variable inductance the variation of which is substantially entirely due to variation in the mutual field between the separate portions of this inductance. Thus, if in Fig. 2 coils R and S are so far apart that the shield O does 60 not markedly change their self inductances on its introduction, yet it may substantially eliminate the assisting mutual inductance. Therefore, in accordance with well known theory, the introduction of the shield O will 65 reduce the total inductance between termi-

nals of the coils R and S by twice the mutual inductance which it has eliminated.

If coils R and S in Fig. 2 were so wound that their fields opposed (instead of assisting as previously), the effect of introducing 70 the shield O will be to lower their self inductances and to diminish their (subtractive) mutual inductance. In the absence of further specifications, it is not possible to decide how the inductance between the coil 75 terminals would vary in this case; since the insertion of the shield tends to diminish this total inductance so far as the reduction of the self inductances of the coils is concerned, but, on the other hand, tends to increase the total inductance between the coil terminals by cutting down the opposing or subtractive mutual inductance. I am well aware of the nature and use of this 80 special disposition of inductances and shields, and regard it as a special case coming under my broad claims hereunto annexed.

85 It is to be understood that the shield O in the figures so far described may be moved or manipulated by any suitable form of operative mechanical means (not shown), and the outline or contour of the shield, and its conductivity are determinable at will, so that practically any desired law of 90 inductance variation with a given series of settings of the shield may be obtained. Furthermore, practically any known law of 95 mutual inductance variation can be similarly obtained by the proper choice of the same 100 conditions.

105 Fig. 4 illustrates another practically useful form of the invention in which the spiral T lies between two shields O and preferably in contact or nearly in contact with them. Under these conditions practically the entire self-flux of the magnetic lines of force of the coil T will pass through the two shields and a reduction in inductance will 110 be caused by the presence of the said two shields. These shields may be slid into or out of the field by means of the handle T' and will give rise to a continuous variation 115 of inductance between the limits obtainable with this device.

120 In Fig. 4 the shield O' is provided with a lug a through which passes the shaft b having the handle c for rotating the shield about the axis of the shaft b to and from the coil T. In so doing, the interlinkage of magnetic flux due to coil T with the shield O' will be continuously varied, thereby varying the inductance of the coil.

125 Fig. 5 shows an arrangement wherein flat spiral coils g, h, j, and k, are provided. The shields o, p, and q, may consist of flat plates adapted to be slid into and out of cooperative relation with the coils. The coils g and h are preferably arranged so 130 that their fields assist, as are also coils

j and *k*. Furthermore, coils *g* and *j* are preferably arranged so that their fields assist, as are also coils *h* and *k*. All four coils are preferably connected in series as shown. When the shields *o*, *p*, and *q* are slid opposite the coils as indicated in the figure, not only the self-fields but the mutual fields are short circuited by the inductance shields. Thus, both their self and mutual inductances are, to a very considerable extent, eliminated. Such sets of coils may be constructed with an unusually high maximum to minimum inductance on shielding, under practical operating conditions. Obviously, more than four coils can be used in this way, and the two piles of coils may be extended into several piles of a very considerable number of coils vertically.

The entrant edge or advancing contour of the shield of conducting material which passes over or into the inductance is of importance in that it determines, in part, the law connecting the motion of the shield and the inductance of the coil which is being shielded. In Fig. 6 the shield *r* which is advancing over or into the coil *s* has an approximately semi-circular edge *t*, because I have found that the law of inductance variation of the coil is more desirable with such an edge than with a straight edge. The drop of inductance with the curved edge is more gradual and extends more nearly evenly over the entire range of motion of the shield. Another even more important advantage is that the increase in resistance, during shield insertion, as well as the terminal resistance is considerably less. This is to be ascribed to the nature of the eddy current paths in the shield *r*, which becomes clear upon a detailed examination of them.

It is sometimes convenient to use a shield *v* which swings over a spiral inductance as shown in Fig. 7, instead of sliding lineally over the spiral. The shield *v* of which there may be several as desired, is pivoted as *u*, and the inductance is a minimum when the shield is swung entirely over the coil and a maximum in the position indicated in the figure. In Fig. 8 is shown a generally preferable contour for a swinging shield *v'*, which outline gives a more gradual drop of inductance of the coil *T* as against angular rotation of the shield, and in addition, gives a smaller increase in the effective resistance of the coil when operatively shielded, as explained in connection with Fig. 6.

In Fig. 9 is shown a way in which double flat spiral coils *x* and *y* may be connected for use as a shield inductance. The inner terminals of the two spirals *x* and *y* are preferably connected at *z* and the spirals should preferably be wound so that their fields will assist with the arrangement

shown. Shields 2 and 3 are adapted to slide or rotate over the spirals in one of the ways illustrated herein. The advantages of the connection of the double spiral shown are that there is a minimum increase of effective resistance for positions of partial shielding and both terminals of the double spiral are conveniently located on the outside of the shields.

In Fig. 10 are shown two flat spirals 4 and 5 connected in series with their fields adding as in the case of Fig. 5. The shield 6 pivoted at 7 is adapted to swing through an angle of approximately 180° over both these spirals 4 and 5. By this means the inductance of both coils 4 and 5 will be greatly reduced and the effective inductance continuously diminished as the shield is swung through an arc of 180° from the position shown. The advantages of the arrangement indicated in Fig. 10 are that it enables ordinary (or slightly altered) plates of a variable condenser to be used as shields of the inductance with a very effective utilization of the supporting space for the coils, which gives a large variable inductance within a limited volume and area. A pile of such units shown in Fig. 10 may be assembled to advantage as in Fig. 5. The modification of Fig. 8 will merely consist in providing rotating or swinging shields instead of lineally sliding shields, which modification was referred to in describing Fig. 5.

In Fig. 11 is shown an extension of the form of apparatus indicated in Fig. 7. In Fig. 11, in addition to the shield inductance formed by the coil *T* and shield *v*, I have illustrated a combined arrangement of shield inductances for the coupling coils 8 and 9 which is also a variable shield mutual inductance, because the primary coil 8 which is variable by means of the shields, is coupled to the similarly variable secondary 9 through a variable shield mutual inductance.

In this instance the shields 10, 11, and 12, are arranged adjacent and between the coils 8 and 9 as indicated and adjustably mounted by means of set screws 13 on a common operating shaft adapted to be manipulated by the handle 15 to swing the shields into and out of shielding position. The shields 10, 11, and 12 need not necessarily be on one operating shaft, but may be independent of one another or else mutually interconnected in any desired manner. The construction shown forms a uni-control variable coupler and variable inductance combined. In Fig. 11, I have illustrated an aperiodic secondary 9 across which in this instance is connected the detector *G* and fixed condenser 16, the telephones *H* being connected as shown across the condenser 16. If desired the shaft *w* of the shield *v* for the loading

coil T may be operatively connected to the shaft 14 of the shields 10, 11, and 12 by any suitable means as the belt or chain 16, so that a completely uni-control device is produced. As the wave length is increased by increasing the inductance of all the coils T, 8 and 9, the coupling between coils 8 and 9 will also be automatically increased by the proper amount. It is to be understood that the design of Fig. 11 is merely illustrative and the arrangement and shape of the various shields, shield inductances, and variable shield mutual inductances may be varied in accordance with any of the modifications herein disclosed, or changed in various particulars in accordance with the principles of my invention, without departing from the spirit of the invention as claimed by me in the claims forming part of this specification.

While I have shown various special forms of application of a shield inductance to uni-control or multi-control receivers and transmitters of various types, I am not to be restricted to the particular forms shown, but desire to be understood as including within my invention, shield inductances, or combinations of shield inductances and shield couplers in different forms in any receiver or transmitter to which they are applicable. The application of this principle as applied to vary the coupling in any receiver or transmitter is made the subject matter of my copending application Serial No. 314,480.

I claim and desire to obtain by Letters Patent the following:

1. A variable inductance for high frequency currents comprising, a pair of spaced coaxial parallel air core coils connected together and a flat shield of conducting material located between said coils, said coils and shield being slidable relative to each other in a direction transverse to the axis of the coils.

2. A variable inductance for high frequency currents comprising an air core coil and a flat shield of conducting material in the magnetic field of said coil, said coil and shield being slidable relative to each other

in a direction transverse to the axis of said coil.

3. A variable inductance for high frequency currents comprising a flat air core coil and a flat shield of conducting material substantially parallel thereto and slidable relative to each other in a direction transverse to the axis of said coil.

4. A variable inductance for high frequency currents comprising a flat air core coil and a flat shield of conducting material substantially parallel thereto, said shield being adjustable in a direction transverse to the axis of said coil to cover various sections of the surface of the coil.

5. A variable inductance for high frequency currents comprising a flat air core coil and a flat shield of conducting material substantially parallel thereto, said conducting body being slidable about an eccentric axis in a direction transverse to the axis of said coils.

6. A variable inductance for high frequency currents comprising a flat air core coil and a flat shield of conducting material substantially parallel and in close proximity thereto, said coil and shield being slidable relative to each other in a direction transverse to the axis of said coil to cover various sections of the surface of the coil.

7. A variable inductance for high frequency currents comprising a pair of adjacent flat substantially parallel air core coils connected together and in close proximity and a flat shield of conducting material intermediate to the coils, said coils and shield being slidable relative to each other in a direction transverse to the axis of said coils to cover various sections of the surface of said coils.

8. A variable inductance for high frequency currents comprising a pair of adjacent flat substantially parallel air core coils connected together and in close proximity and a flat shield of conducting material slidable between the coils in a direction transverse to the axis of said coils.

In testimony whereof I have signed this specification.

ALFRED NORTON GOLDSMITH.
